RECEIVING ROLL

Marion W. Heiss, Greensboro, N. C., assignor, by
mesne assignments, to Cone Mills Corporation,
Greensboro, N. C., a corporation of North
Carolina

Application January 25, 1947, Serial No. 724,312

4 Claims. (Cl. 139—308)

1

This invention relates to a novel method of, and an apparatus for, winding up a substantially endless web of textile material such as cloth woven on a loom or knitted material produced in a warp or tricot knitting machine.

It has been a long standing practice in the weaving industry to have a large number of automatic looms tended by a single weaver who is charged with the performance of various duties incidental to the weaving of first quality cloth. These duties include the stopping of looms that are mechanically out of order or weaving substandard cloth and flagging or otherwise notifying the loomfixer assigned to his looms whose duties include maintaining and keeping looms in such repair that standard, first class cloth can be woven. In the conventional loom, the visible path of the cloth from the fell to the receiving roll is relatively short so that the capacity of a weaver, loomfixer, supervisor or others to note errors in the weaving of a large number of looms and to take appropriate corrective action is quite limited. This limitation on the capacity of the weave room personnel to inspect the goods woven by a battery of looms has existed for many years, but to date no adequate solution for enhancing the capacity for inspecting the goods has been perfected. As a result, additional time, space, equipment and personnel must be made available since each roll of cloth wound on a receiving roll in the conventional manner must be rewound or otherwise handled so that it can be given careful inspection before finishing or shipping. Such inspection must of necessity be made at some other place on another machine, and after a lapse of considerable time after weaving when quality control of the cloth cannot be as quickly or effectively applied.

The receiving roll on which the woven goods are wound on the conventional loom is mounted within the frame of the loom beneath, and sometimes in frictional contact with, the tensioning or sand roll, which draws the goods out of the loom against the action of the brake band on the warp beam. The complicated mechanism of a conventional loom that must of necessity be contained within its framework and the permissible height of the loom above the floor, from an operational point of view, limits considerably the space that is available to the receiving roll. As a result, receiving rolls that are obtained from conventional looms are limited in size so that usually no more than about 200 yards of goods can be wound on a roll. At this point the roll must be doffed from the loom and a new roll must be started.

It is an object of the present invention to provide apparatus for and a method of winding up the goods woven by a conventional loom in such a manner that a relatively large area of the

2

goods is visible at all times to inspectors, supervisors, weavers and loomfixers so that their capacity for detecting flaws in the goods is enhanced to such a considerable degree that the rewind inspection can be avoided entirely and correction can be made before an appreciable quantity of substandard cloth is woven so as to insure quality production. By achieving this object, the causes of substandard weaving can be determined immediately and the responsibility therefor can be definitely placed, thereby enabling a mill to better evaluate the operatives involved and to supervise, instruct, and train them.

Another object of the present invention is to provide apparatus for and a method of winding up the goods on a receiving roll that can take a considerably greater yardage of goods before it must be doffed and another roll started.

It has now been found that these and other objects and advantages can be attained in a novel way by modifying the structure of any conventional loom in such a manner as to wind up the goods on a receiving roll rotated at a peripheral speed substantially equal to the linear speed at which they are produced and positioned at a distance from the loom that is sufficient to give the weaver, loomfixer, inspectors, supervisors and others ample opportunity to discover defects in the weaving and to take appropriate corrective action. In general, the invention contemplates the removal of the conventional receiving roll from within the framework of the loom and the winding up of the goods on a receiving roll at a convenient location under the floor of the weave room. By this means, the conventional placing of batteries of looms along weaver lane within easy reach of the weaver and other personnel is not disturbed and a relatively great length of goods is visible as the goods come off the loom. Furthermore, it provides an arrangement that minimizes interference between the operation of the loom and the doffing of wound rolls of goods because these operations are carried out on different levels.

Although in the following detailed description and in the accompanying drawing the invention is described and illustrated particularly as applied to the winding up of greige goods as they come from the loom, it is to be clearly understood that the invention is not limited to such application but may be applied equally well to other machinery such as is used for warp or tricot knitting.

The foregoing and other objects, the utility and advantages of the invention will become apparent from the following description and from the accompanying drawings wherein:

Figure 1 is a front elevation of a conventional loom modified in accordance with the principles of this invention;

Figure 2 is a section taken along section line 2-2 of Figure 1; and

Figure 3 is a part-sectional view similar to Figure 2 but showing an alternative arrangement for winding up the web.

The loom shown in Figure 1, mounted upon floor 10 of the weave room, is a conventional loom such as a Northrop loom having side frame members 11, an arch 12, harnesses 14 and 16 of the usual strap and roller connection comprising straps 17 and 19 and rollers 20. The loom is equipped with the conventional warp beam 21, from which the yarn 22 passes over the whip roll 24 through lease rods 26, harnesses 14 and 16, and the usual lay and reed, and over and around a tensioning roll 27, sometimes also referred to in the art as a sand, friction, or draw roll. The tensioning roll 27 is driven by a train 29 of gears shown schematically in Figure 2 and which are moved by a drive shaft 30 or any other suitable source of power. These parts of the loom are well known and form no part of the present invention. The innumerable details of a conventional loom have been omitted from the drawing because they are unnecessary to a proper understanding of the present invention and would in fact detract from the prominence given to the illustration of the inventive features.

One modification of the present invention, as specifically illustrated in Figures 1 and 2, comprises supporting a floating receiving roll 31, below floor 10 of the weave room and upon a wind-up roll 33, within a pair of V-frames 32 bolted or otherwise affixed to the underside of floor 10. Receiving roll 31 is wound onto cloth shell 34 which may, if desired, consist simply of a hollow paper or cardboard tube. A shaft 36 is provided to support cloth shell 34. Each end of shaft 36 protruding from cloth shell 34 is adapted to rest freely against one of the dependent members of each V-frame 32. Each pair of V-frames 32 is maintained in suitable spaced relation by means of a spacer bar 37 and provided with a set of bearing blocks 39 designed rotatably to support shaft 40 of wind-up roll 33. One end of wind-up roll 33 and the same end of tensioning roll 27 are provided with sprockets 41 and 42 of equal size and said sprockets 41 and 42 are connected by an endless sprocket chain 44 that passes through hole 45 in floor 10. The diameter of wind-up roll 33 is preferably made the same as that of tensioning roll 27 so that the peripheral speeds of tensioning roll 27 and wind-up roll 33 will be approximately equal. Shims 46 or other appropriate means of adjustment may, if desired, be provided between bearing blocks 39 and the horizontal members of V-frame 32 so as to facilitate adjustment of the tension in chain 44.

In operation, wind-up roll 33 is driven by means of chain 44 and sprockets 41 and 42 at substantially the same or slightly higher peripheral speed and in the same direction as tensioning roll 27. The greige goods pass over tensioning roll 27 downwardly through cloth guard 49, through a slit 50 in floor 10, around wind-up roll 33, and between receiving roll 31 and wind-up roll 330, to be wound up on the former. A polished insert 53 suitably curved to avoid a sharp bend in web 47 may, if desired, be fitted into slit 50 as shown to minimize abrasive action on web 47. Wind-up roll 33 drives receiving roll 31 by frictional contact. As the diameter of receiving roll 31 increases, shaft 36 which rests freely against one side of V-frame 32, rides up along said side of said V-frame. When a pre-

determined yardage of goods has been wound on receiving roll 31, said roll and, if desired, the cloth shell, may be doffed by any suitable means.

It has been found that up to about 2,000 yards of goods can be wound up on a single receiving roll 31 before it need be removed from V-frames 32 by a hand truck or the like, that rolls of such size can easily be subjected to further finishing operations, and that garment workers find it advantageous to use such large rolls.

It is apparent from the foregoing description that the woven goods are visible to the operator of the looms from the fell, i. e., the point at which the lay beats up the filling at each pick 15 of the loom, until they enter cloth guard 49. While the speed of the loom depends upon its model or construction, the width of the goods and upon the material that is woven, it has been found that in weaving a 42 inch wide web of 20 cotton on an X model Draper loom, the goods travel through this distance in about ten minutes, thus giving ample time to check on the operation of a large number of looms inasmuch as inspection of the area described can be carried out almost at a glance. Furthermore, personnel stationed on the floor below have exposed to their view an area of goods equal to or greater than that seen above the floor. By lengthening the V-frames and by other arrangements, 25 greater inspection surfaces can be provided below the floor. The V-frames 32 can conveniently be given the same number as the loom on the floor above and the downstairs personnel can quickly inform the operators upstairs if the goods 30 from any particular loom are woven defectively. This provides a double check of the quality of goods produced and is an important added advantage of the invention. A source of light 35 may also be placed behind the woven goods at any point along the path to assist in the visual inspection and, if desired, light sensitive means may be employed in cooperation therewith to automatically mark thin places in the goods, to stop the loom, or to otherwise call the attention 40 of the operator to such defects in the weave.

It is to be understood, of course, that the term "receiving roll," as used herein, is intended to include any roll upon which the material may be wound either temporarily or for shipping purposes. It is sometimes also referred to in the art as a package roll or cloth roll.

The term "tensioning roll," as used herein, is a generic term to designate any type of roll that is used to pull the woven or knitted goods through the machine and is variously referred to in the art as a sand roll, friction roll, draw roll, etc.

It is obvious that upon reading the foregoing description of the invention, many changes, alternatives and modifications will occur to those skilled in the art of weaving. Thus, for example, the travel of the goods immediately after the filling is beaten up may be considerably different, depending upon the particular type of loom that is used. The goods may travel over a breast beam, and idler roller, then around a tensioning roll and perhaps around another idler roller before it is passed through the floor to be wound up on the receiving roll. Idler rolls may also be positioned adjacent the slit in the floor to minimize rubbing of the goods against the flooring. Instead of passing the goods around the wind-up roller before they are wound up on the cloth shell, they may be wound directly upon the receiving roll, as illustrated schematically in Figure 3. In that event the drive for the wind-up roll should be re-

versed so as to rotate it in the direction opposite to that of the tensioning roll. This may be accomplished simply by crossing chain 44 or by using the sprocket of a reversely rotating shaft to drive the chain. The diameter of the tensioning roll and the wind-up roll need not be substantially equal so long as the drive is such as to provide for rotation at approximately equal peripheral speeds.

It is also quite possible to vary the drive for the wind-up roll in many different ways. It may be driven by means of a shaft and bevel gear arrangement, by a worm gear and shaft drive, or by a V-belt and sheave drive. The chain or equivalent drive, instead of being taken from the tensioning roll, may be taken from any other rotating shaft, such as from a gear or sprocket driven by the pick gear train, or by a ratchet wheel with an actuating pawl driven by cam action from an eccentric on the main shaft of the loom. It is also quite possible to provide an individual drive for the wind-up roll, such as by means of a constant torque motor driving the shaft through a worm gear or the like or to eliminate the wind-up roll entirely and drive the receiving roll directly through a suitable clutch, constant torque motor or the like that will operate to rotate the receiving roll with a peripheral speed approximately equal to the peripheral speed of the tensioning roll.

The V-frame arrangement on which the receiving roll is supported may also be varied considerably. Thus, for example, a trapezoidal frame may be supported on the floor below the weave loom floor to support two or more receiving rolls from opposite or adjacent looms on the floor above. The shaft of the cloth shell need not necessarily float or ride freely along an inclined member of the supporting frame but may be guided vertically between channel members. When the shaft of the cloth shell is so mounted, it may be desirable to pass the cloth over one or more idler or guiding rolls before it is wound up on the receiving roll. It is also within the contemplation of this invention to provide the shaft for the cloth shell with gears that will mesh with gears on the shaft of the wind-up roll so that proper winding up of the first layers of goods on the receiving roll will be assured even though the weight of the receiving roll may not at the time be sufficient of itself to insure a tight winding of the goods thereon. It is also quite possible to provide a tensioning device between the cloth roll and the lower portion of the support frame or the wind-up roll to insure proper winding up of the goods, especially in the initial stages.

All such modifications, alterations and variations of the invention are intended to be included as come within the scope of the appended claims.

I claim:

1. In combination with a flat loom supported upon a floor, an aperture in the floor to permit the passage therethrough of a flat web delivered by the loom, and a take-up device suspended below the floor comprising a frame having a pair of parallel, inclined members, a wind-up roll rotatably supported in the lower portion of said frame, a floating receiving roll resting upon the wind-up roll and having shaft ends resting freely against said inclined members, and means for rotating said wind-up roll to rotate the receiving roll at

a peripheral speed substantially equal to the speed at which the flat web is delivered by the loom whereby the flat web is wound up on the receiving roll after a considerable length of the web has been exposed for inspection.

- 5 2. In combination with a flat loom supported upon a floor, an aperture in the floor to permit the passage therethrough of a flat web delivered by the loom, and a take-up device below the floor comprising a frame, a wind-up roll rotatably supported in said frame, a floating receiving roll supported in said frame and urged into peripheral contact with said wind-up roll, and means for rotating said wind-up roll to rotate the receiving roll at a peripheral speed substantially equal to the speed at which the flat web is delivered by the loom, whereby the flat web is wound up on the receiving roll after a considerable length of the web has been exposed for inspection.
- 10 3. In combination with a flat web forming textile machine supported upon a floor, an aperture in the floor to permit the passage therethrough of a flat web of textile material delivered by the machine, and a take-up device below the floor comprising a frame, a wind-up roll rotatably supported in said frame, a floating receiving roll supported in said frame and urged into peripheral contact with said wind-up roll, and means for rotating said wind-up roll to rotate the receiving roll at a peripheral speed substantially equal to the speed at which the flat web is delivered by the machine, whereby the flat web is wound up on the receiving roll after a considerable length of the web has been exposed for inspection.
- 15 4. In combination with a flat web forming textile machine supported upon a floor, an aperture in the floor to permit the passage therethrough of a flat web of textile material delivered by the machine, a take-up device below the floor comprising a frame, a receiving roll rotatably supported in said frame and means for rotating the receiving roll at a peripheral speed substantially equal to the speed at which the flat web is delivered by the machine, whereby the flat web is wound up on the receiving roll after a considerable length of the web has been exposed for inspection.
- 20 5. In combination with a flat web forming textile machine supported upon a floor, an aperture in the floor to permit the passage therethrough of a flat web of textile material delivered by the machine, a take-up device below the floor comprising a frame, a receiving roll rotatably supported in said frame and means for rotating the receiving roll at a peripheral speed substantially equal to the speed at which the flat web is delivered by the machine, whereby the flat web is wound up on the receiving roll after a considerable length of the web has been exposed for inspection.
- 25 6. In combination with a flat web forming textile machine supported upon a floor, an aperture in the floor to permit the passage therethrough of a flat web of textile material delivered by the machine, a take-up device below the floor comprising a frame, a receiving roll rotatably supported in said frame and means for rotating the receiving roll at a peripheral speed substantially equal to the speed at which the flat web is delivered by the machine, whereby the flat web is wound up on the receiving roll after a considerable length of the web has been exposed for inspection.
- 30 7. In combination with a flat web forming textile machine supported upon a floor, an aperture in the floor to permit the passage therethrough of a flat web of textile material delivered by the machine, a take-up device below the floor comprising a frame, a receiving roll rotatably supported in said frame and means for rotating the receiving roll at a peripheral speed substantially equal to the speed at which the flat web is delivered by the machine, whereby the flat web is wound up on the receiving roll after a considerable length of the web has been exposed for inspection.
- 35 8. In combination with a flat web forming textile machine supported upon a floor, an aperture in the floor to permit the passage therethrough of a flat web of textile material delivered by the machine, a take-up device below the floor comprising a frame, a receiving roll rotatably supported in said frame and means for rotating the receiving roll at a peripheral speed substantially equal to the speed at which the flat web is delivered by the machine, whereby the flat web is wound up on the receiving roll after a considerable length of the web has been exposed for inspection.
- 40 9. In combination with a flat web forming textile machine supported upon a floor, an aperture in the floor to permit the passage therethrough of a flat web of textile material delivered by the machine, a take-up device below the floor comprising a frame, a receiving roll rotatably supported in said frame and means for rotating the receiving roll at a peripheral speed substantially equal to the speed at which the flat web is delivered by the machine, whereby the flat web is wound up on the receiving roll after a considerable length of the web has been exposed for inspection.
- 45 10. In combination with a flat web forming textile machine supported upon a floor, an aperture in the floor to permit the passage therethrough of a flat web of textile material delivered by the machine, a take-up device below the floor comprising a frame, a receiving roll rotatably supported in said frame and means for rotating the receiving roll at a peripheral speed substantially equal to the speed at which the flat web is delivered by the machine, whereby the flat web is wound up on the receiving roll after a considerable length of the web has been exposed for inspection.
